UNITED STATES PATENT OFFICE.

ISAAC S. PURCELL, OF CHICAGO, ILLINOIS, ASSIGNOR TO TENTOBED COMPANY, OF CHICAGO, ILLINOIS, A CORPORATION OF ILLINOIS.

FOLDING TENT.

1,285,791.

Specification of Letters Patent. Patented Nov. 26, 1918.

Application filed June 20, 1917. Serial No. 175,756.

To all whom it may concern:

Be it known that I, ISAAC S. PURCELL, citizen of the United States, residing at Chicago, Illinois, have invented certain new and 5 useful Improvements in Folding Tents; and I do hereby declare the following to be a full, clear, and exact description of the invention, such as will enable others skilled in the art to which it appertains to make and 10 use the same.

My invention relates to folding tents, one of its general objects being to provide a tent carrying its own frame and requiring no poles, and one that can readily be folded or 15 rolled (with the bracing included) into an unusually compact space. Another object is to provide a foldable tent frame the elements of which will be straight when the frame is not erected, but in which certain frame elements will assume curves when the frame is 20 erected, thereby affording an unusually handsome appearance to the tent and unusually large effective space within a tent of a given height and width. Furthermore, 25 my invention aims to provide a tent and frame combination which can readily be attached either to a folding cot, thereby forming a hooded cot, or to cross-bars to form a decidedly superior substitute for a so-called 30 "pup" tent. Moreover, my invention aims to provide simple means for securing the frame members to the tent, for preventing the frame-curving strains from damaging the sockets for the latter, for limiting the 35 insertion of the frame members into the sockets, for connecting certain frame members to each other while permitting the ready erecting and compacting of the same, and for tensioning the ridge of the tent. 40 Still further objects will appear from the following specification and from the accompanying drawings, in which—

Figure 1 is a perspective view of one embodiment of my invention, showing the same 45 as used in connection with a folding cot.

Fig. 2 is a transverse section through the tent or Fig. 1 along the line 2—2.

Fig. 3 is an enlarged fragmentary inner view of an edge portion of the side of the 50 tent of Fig. 1.

Fig. 4 is an enlarged view of the jointed ends of each pair of the frame members as they appear when the tent is erected.

Fig. 5 is an enlarged fragmentary end 55 view of tent portions, showing parts of side

and end rails of the bed, and of one of the frame members.

Fig. 6 is a view taken at right angles to Fig. 5.

Fig. 7 is a central vertical section through Fig. 6.

Fig. 8 is a transverse section through Fig. 3.

Fig. 9 is a perspective view of one of the three sets of frame members as used with a "pup" tent embodying my invention.

Fig. 10 is a fragmentary view showing another method of slidably connecting the ribs with the tent sides.

In my copending application, filed Oct. 7, 1916, as Serial No. 124,216, I have disclosed a tent suitable for use with a folding cot, this tent being slipped over a skeleton frame composed of straight steel bars. With such a construction, the frame and the 75 tent must be erected separately, and in practice the combination has proven to be objectionable in weight. Moreover, the acute angles between the frame members and the bed-bottom permit the tent to follow the 80 same angles, thereby practically wasting a considerable portion of the width of the bed-bottom along each edge of the latter.

My present invention aims to provide a substitute for the construction just referred to and one which will simultaneously avoid the waste of space, the excessive weight, and the separate handling of the frame and of the tent. With this in view, I construct the frame of my present tent in pairs of pivotally connected and normally straight members, each of which members is desirably made of round spring steel. For ordinary sized tents, I provide three such pairs of members (viz., one for each end of the 90 tent and one for the middle) and connect each pair operatively to the tent by slipping each member thereof through a tube formed by sewing a piece of canvas 6 vertically to the inner face of the tent as shown in Figs. 100 3 and 8. Each of these tubes terminates somewhat below the ridge of the tent and somewhat above the bed-bottom, thus permitting both the jointed and the free ends of the rod members 1 to be exposed at the 95 inside of the tent. I then provide suitable sockets for receiving the free ends of the rod members, as for example by boring holes through the side rails 2 of the cot.

However, these holes are not bored in direc- 110

tions which would align with the proposed position of the ridge of the tent, but are bored vertically, thus compelling the rods to be flexed to curves when inserting their ends 5 into these bores or sockets. When thus inserted, the flexed rods bow after the general manner of Gothic arches, thereby affording the unusual and handsome appearance which will be evident from Fig. 1. More- 10 over, since the lower ends of the rods are vertical and the portions adjacent to them gradually curve away from the vertical, the bowed frame members hold the tent out so as to afford a tent space practically equal to 15 the width of the bed-bottom for some distance above the latter. In other words, they increase the effective width of the tent and also decrease the danger of having occupants of the tent strike the tent sides and 20 thereby cause the tent to leak in wet weather.

To limit the extent to which each of the frame rods 1 is slipped into one of the said sockets, I provide suitable stops. The upper ends of the legs 3 underlie the sockets provided for the rods 1 in side rails 2 and by engaging the tips of the free ends of the rods limit the insertion of the latter into the sockets. The sockets are formed near the corners of the frame. I also desirably form 25 the required socket bore in the location shown in Figs. 6 and 7, so that the rivets 4 which secure the pivot plates 5 to the side rail 2 of the cot will coöperate with these pivot plates in practically armoring the 30 socket. However, the curving of the rod 1 and the consequent pressure of the same against one edge of the bore right where it leaves the latter would still tend to indent the wood and to correspondingly elongate 35 the section of the bore. To guard against this, I preferably reinforce the side rail 2 by a steel bushing 7 as shown in Figs. 6 and 7.

With the socket bores for the two free 45 ends of each two-piece frame portion bored vertically and at points located opposite each other on the two side rails, it will be obvious that the bowed legs of each erected frame portion will be substantially in a 50 common vertical plane. Consequently, these suitably spaced pointed arches will in themselves tend to maintain the tent extended lengthwise. However, I preferably provide auxiliary ridge tensioning means in the form 55 of ropes 8 secured respectively to the joints of the end frames (as by attaching to the eye 9 of the swivel pin in Fig. 3), which ropes are then fastened to suitably placed trees or stakes. In this manner I am able 60 to secure a substantially taut ridge without using any ridge pole whatever and without even providing ropes or the like as connections between the swivel joints of consecutive pairs of frame members.

65 Where the tent of my invention is to be

used upon a cot, the side rails 2, are suitably spaced by the sliding of their ends through sockets 10 at the ends of the end rails 11 from convenient supports for the frame members of my tent. For "pup" tents, a 70 simple wooden bar 12 equipped at each end with a vertical bore answers the same purpose, as in Fig. 9, such a bar being easily sunk into the ground sufficiently to leave a 75 level surface for the bedding.

In either case, it will be obvious that by extending each frame rod through tubular tent wall portions, the tent sides can slide more or less upon these rods to adjust themselves, so that it is easy to secure a smooth 80 tent surface over the bowed rods and also easy to smooth the tent sides out over the rods when these are free to straighten. Consequently, the disassembled tent can readily be 85 rolled, rods and all, into an unusually compact parcel, and as relatively small rods are ample in size for this purpose, the total weight required is much less than that of the tent supports heretofore used. I am 90 therefore able to provide outfits sufficiently 95 light to be carried even by boy scouts, and also to obtain a given effective tent capacity with a narrower bed-bottom than that required with straight-sided frames.

However, while I have pictured and described my frame-support as including three jointed pairs of rods, and the ridge tensioning ropes as secured to pivot rings, I do not wish to be limited to these or other details of the construction and arrangement 100 here disclosed, it being obvious that the same might be modified in many ways without departing from the spirit of my invention. For example, Fig. 10 shows a substitute for the canvas strip 6 of Fig. 3, namely a pair 105 of cloth or leather tabs 13 secured to the side of the tent and each having an eyelet 14 through which one of the rods is held in position with respect to the side of the tent.

I claim as my invention:

1. A tent frame including a pair of normally straight members pivotally joined at their upper ends and diverging from said joint when in use, and a pair of sockets for the lower ends of said members, the sockets 115 being disposed for inwardly flexing the said ends and thereby coöperating with the pivotal joining of the said members to bow the latter into a Gothic arch formation.

2. A tent frame including a pair of normally straight members pivotally joined at their upper ends and diverging from said joint when in use, and a pair of substantially parallel sockets entered by the lower ends of said members, whereby the parallelism of the said sockets compels a bowing 125 of the said members while leaving the latter adjoined in a peak formation at their said pivotal junction.

3. A tent frame including a pair of resili- 130

ent and normally straight members pivotally joined at their upper ends and diverging from said joint at an acute angle to each other when in use, and spreader means 5 equipped at opposite ends with substantially parallel sockets for receiving the lower ends of said members, whereby the angular adjoining of the upper ends and the parallel socketing of the lower ends coöperate in 10 bowing the said members.

4. A tent frame including a pair of normally straight members of resilient material pivotally joined at their upper ends to afford a peak formation, and a pair of 15 sockets housing the lower ends of the said members, the said sockets being directed respectively past opposite sides of the pivotal junction of the said members and thereby compelling a bowing of the said members 20 into substantially a Gothic arch formation.

5. A tent frame as per claim 3, in combination with symmetrically disposed means for limiting the entrance of the lower ends of the said members into the sockets and 25 thereby effecting a symmetrical disposition of the said members.

6. Tent frame elements as per claim 1, in combination with a tent having oppositely sloping portions equipped with tubular formations through which the respective members extend and whereby the said members are continuously maintained within the 30 folds of the tent when the latter is dismantled, thereby permitting the dismantled

tent to be compacted with the said frame elements in their normal straight formation.

7. In combination, a tent equipped on each of two oppositely sloping sides with a plurality of tubular formations, normally 40 straight tent ribs of resilient material arranged in pairs pivotally joined at their upper ends near the ridge of the tent and disposed with the members of each pair extending respectively through said tubular 45 formations on the opposite tent sides, a support for the tent, and plural socketing means upon each side of the support for receiving the ends of the said ribs, the socketing means receiving the ends of each pivotally joined pair of ribs being directed 50 away from the pivotal junction of the ribs so as to compel a bowing of the ribs and the tent sides into a Gothic arch formation.

8. A tent support comprising a substantially horizontal and rectangular frame equipped near its corners with substantially vertical socket formations, members each comprising a pair of pivotally adjoined parts socketed at their free ends in a pair 55 of the said sockets, and legs pivoted to the frame and disposed respectively for engaging the tips of the said free ends of the 60 said members to limit the insertion of the latter into the socket members.

Signed at Chicago, June 15th, 1917.

ISAAC S. PURCELL.
